UNITED STATES PATENT OFFICE.

EUNICE SUTTON, OF NEW YORK, N. Y., ASSIGNOR TO SUTWA MFG. CO., INC., OF NEW YORK, N. Y., A CORPORATION OF NEW YORK.

DISPLAY DEVICE.

Application filed April 11, 1922. Serial No. 551,546.

To all whom it may concern:

Be it known that I, EUNICE SUTTON, a citizen of the United States, and a resident of New York city, in the county of New York and State of New York, have invented certain new and useful Improvements in Display Devices, of which the following is a specification.

This invention relates to a display device and more particularly to a device for displaying the make, construction and style of certain articles of merchandise such as wearing apparel and the supporting hangers therefor; and has special reference to the provision of a novel means for attractively displaying such articles to portray the make and style thereof and to teach the manner of using the same.

A principal object of my present invention comprehends the provision of a display such as a window display in which wearing apparel is attractively presented to the view of the observer in such a manner that the make and style of a garment and the correct manner of supporting or hanging the same when not worn by the user is pleasingly depicted and presented to view.

A further principal object of my invention comprehends the provision of a display in which the correct and intended use of a garment hanger applicable to the garment displayed may be clearly exemplified and shown so that not only may the make of the garment hanger or the style of the garment or both be readily disclosed to view, but so that the purchasing public may be instructed as to the correct way of hanging the garment and using the hanger.

To the accomplishment of the foregoing and such other objects as may hereinafter appear, my invention consists in the elements and their relation one to the other, as hereinafter particularly described and sought to be defined in the claims, reference being had to the accompanying drawing which shows a preferred embodiment of my invention, and in which

The figure is a perspective view of my display device.

Referring in detail to the drawing, my display device comprises essentially a figure F simulating the human form and a garment display G including a garment detached from the figure and supportingly held by the same

in such a manner that the style and make of the garment is fully revealed to an observer and the manner of hanging the garment to preserve and hold the shape of the same is instructively disclosed to view.

The figure F, made of suitable plastic or other material, is preferably a complete figure simulating the human form, the said figure including the body portion 10, a head 11 attractively coiffured, the lower limbs 12 and preferably detachable upper limbs 13 and 14, the figure being attached to and supported on a base or other suitable support 15. The upper limb or arm 13 when attached to the body 10 is preferably made to assume the outstretched position clearly shown in the figure, the said arm being preferably made of a length such that a garment display when suspended therefrom will be held in normally outstretched position and clear from the said figure F, this in simulation of the manner in which a garment is naturally held at arm's length by the user for proper and admiring inspection. The figure F is preferably made in miniature form and comprises a statuette, although it will be apparent that the said figure may be made in larger sizes if desired.

The figure is preferably partially or incompletely attired and to this end the figure may be provided with the undergarment 16 which may, for example, be a chemise suspended by means of the straps 17 from the shoulders of the figure, the said straps preferably overlying and concealing the joints between the removable arms 13 and 14 and the body 10 of the figure, the chemise 16 being preferably fashioned from a transparent material such as a reticulated fabric to permit the shape and contour of the figure to be exposed to view. The lower limbs or legs 12 may be suitably ornamented as shown to portray fashionable hosiery and footwear.

The garment display of my invention comprises preferably a garment hanger 18 detachably and supportingly held by the hand 13' of the arm 13 of the figure and a garment 19 carried by the hanger 18, the said garment 19 being applicable to the figure F and comprising the complementary dress portion necessary for completing the attire for the figure. The garment is thus displayed as a unit independent and de-

tached from the figure, the garment displayed 5
pleasingly indicating and denoting the ad-
ditional apparel necessary for completing
the attire and toilet for the figure, the en-
semble yielding a display highly attractive
to the eye. To further attract and direct the
observer's attention to the garment display,
the head 11 of the figure is so ornamented
as to have the eyes of the same suggestively
10 directed towards the garment display, as
clearly disclosed in the drawing.

For the purpose of depicting the make
and style of both the garment 19 and the
garment hanger 18 and to instructively dis-
15 close to the purchasing public the correct
and intended way of hanging the garment
and of using the garment hanger, my in-
vention includes the employment of a gar-
ment hanger such as 18 which comprises the
20 spaced shoulder and waist members 20 and
21, these members being connected together
by the preferably integral side portions 22
and 23, the shoulder member 20 being intend-
ed for suspendingly supporting the waist
25 portion 24 and the waist member 21 being
intended for suspendingly supporting the
dress portion 25 of the garment 19. The
garment 19 in the present exemplification of
my invention is shown to comprise or to
30 simulate a dress in the form of a lady's
evening gown consisting of the attached
waist and skirt portions 24 and 25. The
shoulder member 20 of the garment hanger
18 supports the waist portion 24 of the
35 dress, the strap or yoke portions 26 usually
forming part of the dress being received
by the shoulder member 20 of the garment
hanger for this purpose. The waist mem-
ber 21 of the garment hanger independently
40 supports the attached skirt 25 of the dress
and to this end the dress is provided with
spaced loops or straps 27 which may be
attached to the waist band of the dress,
these loops being received for suspension on
45 spaced integral loop members 28 provided
in the waist member of the hanger 18. The
shoulder and waist members 20 and 21 of
the hanger are spaced a distance correspond-
ing to the corresponding members of the
50 human body so that the attached skirt
and waist portions 25 and 24 of the dress
are independently supported on the hanger.
This display discloses the desired way of
hanging a garment such as a lady's even-
55 ing gown of the type in which the skirt
portion is made of relatively heavy material
and the waist portion and shoulder straps
made of a light and delicate fabric, the
dress being hung so that the weight of the
60 skirt is removed from the waist and the
waist is permitted to assume its natural
condition as worn by the user, the manner
of suspending or hanging these dress parts
being such that the strains and stresses
65 which otherwise subject the waist and the

strap portions of the dress to the distorting
influence of the skirt are eliminated, this
being an object especially desired in dresses
of this type, the waist being hung, more-
over, in a manner to cause it to assume its
natural folds and ordinary shape, wrinkling
and rumpling of the same being thereby
prevented. 70

For the purpose of showing the construc-
tion and make up of the garment hanger
18, the waist portion 24 of the dress is pref-
erably made of a transparent material such
as a reticulated fabric, this to disclose the
garment hanger as well as the straps 27
suspendedly received thereby, the manner
of hanging the skirt on the hanger being
thereby made clear to the observer. 75

By supporting the garment 19 on the
garment hanger 18 in this described manner,
the garment may be effectively displayed to
the view of the observer, the purchasing
public being additionally instructed as to
the correct way of hanging a garment of
this nature without defacing, despoiling or
distorting the same, the construction and
make-up of the garment hanger being,
moreover, fully displayed to view. 90

The construction and the manner of using
my display device will, in the main, be ap-
parent from the above detailed description
thereof. It will be further apparent that
I have provided a novel means for display-
ing articles of merchandise such as wearing
apparel and the means for supporting or
hanging the same, the wearing apparel such
as a lady's dress being attractively presented
to an observer's view as a complete entity
detached from the figure, the said figure
being preferably incompletely attired with
the garment displayed depicting and the
figure suggesting the completion of the
attire for the said figure. It will be further
seen that the garment is attractively hung
from the garment hanger 18 in such a way
that the correct manner of suspending or
hanging the parts of the garment is fully
revealed, the make up and construction of
the garment hanger and the manner of
using the same being further fully disclosed
in a highly instructive and pleasing manner. 105

While I have shown my device in the pre-
ferred form, it will be obvious that many
changes and modifications may be made in
the structure disclosed without departing
from the spirit of the invention, defined in
the following claims. 120

I claim:

1. In a display, a figure in simulation of
the human form, a garment hanger carried
thereby and having separate means for sup-
porting the waist and skirt of a garment
and a garment on the garment hanger ap-
plicable to the sex represented by the figure,
the garment being of such a character and 125
130

supported on the hanger in such manner that the style of the garment and the manner of supporting the same on the hanger is disclosed to the observer.

5 2. A display comprising an incompletely attired figure simulating the human form, the said figure including a member forming a support and garment display means pendently supported from the said member, with 10 the garment applicable to the figure and indicating the completion of the attire for the said figure.

3. A display comprising an incompletely attired figure simulating the human form, 15 the said figure including a member forming a support and garment display means pendently supported from the said member, with the garment applicable to the figure and indicating the completion of the attire for 20 the said figure, the said member being of a length to support the garment display in outstretched position clear from the said figure and the eyes of said figure being turned towards the garment so as to direct the attention of the observer thereto.

4. In a display, a statuette comprising a figure simulating the human form and provided with incomplete attire, the said figure provided with an arm forming a support 20 and garment display means removably pendently supported from the said arm, with the garment applicable to the figure and indicating the completion of the attire for the same.

25 5. In a display, a figure simulating the human form and provided with partial or incomplete attire, a garment hanger supported on the said figure and a garment applicable to the figure and carried by said 40 garment hanger, the said garment being supported by the hanger in such manner that the style of the garment and the manner of supporting the same on the hanger is disclosed to the observer.

6. In a display, a figure simulating the human form, a detachable garment hanger carried thereby and a garment on the garment hanger applicable to the figure, and of such a character as to disclose the style and 50 make of both the garment hanger and the garment and the manner of supporting the garment.

7. In a display, a figure simulating the human form, a garment hanger carried thereby and a garment on the garment hanger, the garment hanger supporting the garment in a manner to disclose the style

and make of the garment hanger and the manner of supporting the garment.

8. In a display, a figure simulating the 60 human form and provided with partial or incomplete attire, a garment hanger supported on the said figure and a garment applicable to the figure and carried by said 65 garment hanger, the said garment being supported by the hanger in such manner that the style of the garment and the manner of supporting the same on the hanger is disclosed to the observer, the eyes of the said figure being turned toward the garment so 70 as to direct the attention of the observer thereto.

9. In a display, a statuette comprising a figure simulating the human form, the said figure including a body portion and a supporting member and means supported from the said member, the said means including a garment hanger and a garment carried thereby the garment being applicable to the figure and of such a character that the 80 style of the garment hanger and the manner of supporting the garment is disclosed to the observer.

10. In a display, a figure simulating the human form, a garment hanger supported 85 from the said figure and including elements for independently supporting the waist and skirt portions of a garment or dress and a dress on said garment hanger applicable to said figure and comprising waist and skirt 90 portions, the waist portion being sufficiently transparent to disclose to an observer the style of the hanger and the manner of supporting the garment thereon.

11. In a display, a statuette comprising a 95 figure with incomplete attire, the said figure including a body and a member outstanding therefrom and forming a support, a garment hanger removably supported on said member, the said garment hanger including 100 means for independently supporting the waist and skirt portions of a dress and a dress on said garment hanger applicable to said figure and including waist and skirt 105 portions, with the waist portion sufficiently transparent to display the style of the hanger and the manner of supporting the dress, the said dress constituting and forming the completion of the attire for the said figure.

Signed at New York city, in the county of New York and State of New York this 10th day of April, A. D. 1922.

EUNICE SUTTON.
